UNITED STATES PATENT OFFICE.

GEORGE HANNES, OF CINCINNATI, OHIO.

METALLIC WHEEL.

SPECIFICATION forming part of Letters Patent No. 433,621, dated August 5, 1890.

Application filed April 7, 1890. Serial No. 346,991. (No model.)

To all whom it may concern:

Be it known that I, GEORGE HANNES, a citizen of the United States, residing at Cincinnati, in the county of Hamilton and State 5 of Ohio, have invented certain new and useful Improvements in Metallic Wheels; and I do hereby declare the following to be a full, clear, and exact description of the invention, reference being had to the annexed 10 drawings, which form a part of this specification.

This invention relates to those wheels which have "return-spokes" composed of wires or light rods whose bends engage with 15 metallic hubs; and my improvement comprises a novel combination of grooved and pitted hub-plate, a cap having an annular inclined bearing for the spoke-bends to abut against, and a sleeve whose end is upset 20 against the outer face of said cap, thereby binding these members of the wheel securely together, and causing said inclined bearing to exercise a wedging action against said spoke-bends, as hereinafter more fully 25 described.

In the annexed drawings, Figure 1 is a front elevation of the grooved and pitted hub plate or disk. Fig. 2 is an elevation both of the rear and front of the cap having the annular bearing. Fig. 3 is an elevation of the 30 center of the complete wheel, part of the cap of the same being broken away and a portion of the annular bearing and sleeve being sectioned. Fig. 4 is a vertical section through 35 the center of the wheel, which section is taken at the axis of the sleeve.

The principal member of the hub is a metallic plate or disk A, having on its outer face an annular recess B and a practically circular pit C, said disk being bored centrally, as 40 at D, to admit the sleeve E.

F represents a series of grooves in the face of the hub-disk, which grooves slope back and inwardly and are connected by passages 45 f with other grooves F'. These latter grooves also slope back and inwardly, and finally emerge at the periphery of the disk A, by which arrangement the grooves can be readily cast in the disk, thereby avoiding any 50 tedious and expensive drilling operations.

Furthermore, these two-part grooves F F' are in line with each other, so as to cause the return-spokes G to extend directly from the hub to the tire without being bent in any manner, except where the portions g of said 55 spokes are located. These portions or bends are so curved as to be concentric with the flange or annular bearing H on the rear of a disk-shaped cap I, adapted to fit snugly within the recess B of the hub-disk, said flange H 60 being so tapered as to act as a wedge against said bends g, and thereby force the spokes tightly into the grooves F F', as seen in Fig. 4. Cap I has a central circular orifice J to admit the sleeve E, which orifice is reamed 65 out, as seen at K in Figs. 2 and 4, to enable the end e of said sleeve to be upset against said cap, said sleeve being provided with a collar e', that bears against the inner face of the hub-disk, of which latter a pair is employed for each wheel.

In constructing this wheel the return-spokes G are first made so as to have the necessary outward divergence or spread, as seen in Fig. 3, the bends g of said spokes being curved 75 concentric with the center of the hub, so as to fit snugly around the annular flange or bearing H when the spokes are properly fitted within the hub. This act is readily accomplished by passing the spokes through 80 the grooves F F' from the pit C outwardly, and then inserting the cap I within the annular recess B, thereby causing the flange H of said cap to wedge against the bends g of all the spokes. The opposite ends of sleeve 85 E are then passed through the coincident openings D J of the disks and caps and upset, as seen at e e in Fig. 4, thus clamping the caps to the disks and causing the latter to bear immovably against the collars e' e'. 90 The outer ends of the spokes are then cut off, so as to be of uniform lengths, and are secured to an ordinary tire in the usual manner.

From the above description it is apparent this construction affords a light but very 95 strong and durable wheel, which is especially adapted for velocipedes and other similar vehicles, although not limited to such use.

I claim as my invention—

The combination, in a metallic wheel, of 100

the hub-disk A, having a pit C, central orifice D, and a series of grooves F F' extending from said pit to the periphery of said hub, a series of spokes G, inserted within said 5 grooves, a cap I, fitted within said pit and having an annular inclined flange H, which flange wedges against the bends g of said spokes, and a sleeve E, whose end is upset

against said cap and secures the latter to the hub-disk, all as herein described.

In testimony whereof I affix my signature in presence of two witnesses.

GEORGE HANNES.
